UNITED STATES PATENT OFFICE

JOHN ARNOLD STREUN, OF SHERMAN, TEXAS, ASSIGNOR TO HARDWICKE-ETTER COMPANY, A CORPORATION

COTTON GIN RIB

Application filed April 14, 1930. Serial No. 444,028.

My invention relates to cotton gins and has particular application to the ribs cooperating with the gin saw to remove the seed from the lint.

5 In prior structures of this kind it is found that the ribs, between which the gin saws work, are liable to injury or breakage and occasionally have to be removed and replaced. This is a difficult and laborious job 55
 10 with the ordinary type of construction in that the ribs are secured in place by bolts and screws and as they are difficult of access the replacing of a broken or worn rib is difficult. Attempts have been made to make re-
 15 movable gin ribs which may be replaced with less difficulty than in the older structures but in these improved type of ribs it has been found difficult to maintain them in proper alignment and to hold them rigidly in position with the result that none of the improved type of ribs have been entirely successful.

It is an object of my invention to provide a gin rib of such construction that it may be easily mounted or demounted without difficulty making it easy to replace when desired.

It is also an object to provide means for holding the ribs accurately in position so that they may not become out of alignment.

30 It is a further object of the invention to provide an efficient type of rib which in cross section is adapted particularly to effectively remove the seed from the lint and to allow the lint to release from the saw blade.

35 In the drawings herewith Fig. 1 illustrates a broken sectional view through the forward part of a cotton gin showing ribs thereon embodying my invention.

Fig. 2 is a broken front elevation of a portion 40 of a cotton gin illustrating the improved ribs as seen from the forward side thereof.

Fig. 3 is a transverse section on the plane 3—3 of Fig. 1.

Fig. 4 is a similar section on the plane 4—4 45 of Fig. 1, and

Fig. 5 is a similar transverse section on the plane 5—5 of Fig. 1.

In the drawings I have shown a portion 50 of the cotton gin in which my improved rib is employed. The general construction

thereof is not a part of this invention and need not be particularly described. The view shown in Fig. 1 illustrates a forward chamber 1 into which the cotton is fed to be ginned. The lower part of the chamber 1 is provided with an adjustable chute 2 leading to the picker roll 3, which is rotatable to carry the cotton into contact with the gin saws 4.

The gin saw is mounted upon a shaft 5 transversely of the gin and above the saw is 60 a roll chamber 6 to accommodate the cotton roll formed in the ginning operation.

The roll chamber 6 is divided from the forward chamber 1 by a partition 7 of usual construction. The lower part of this partition 65 serves as a mounting for the guide ribs 8, which are mounted at their lower ends upon cross plates 9 below the picker roll.

The gin ribs 10, which form the subject matter of my improvement, are supported 70 at their upper ends upon a transverse rod or shaft 11 extending between the side walls of the gin. At their lower ends they are supported upon a similar transverse rod or shaft 12. The ribs are of the general shape of ribs 75 now in use. That is, they are curved between the ends to correspond somewhat with the curvature of the gin saws which operate between adjacent ribs. This shape will be understood from the view in Fig. 1.

The upper end of each of the gin ribs is formed with a head 13, which has a marginal flange 14 seen best in Fig. 3. Between the flanged outline of the head is a web 15, said web being slotted or forked at 16 to engage 80 about the shaft 11. This slotted end when the rib is in proper position is inclined downwardly at a slight angle so as to better engage the rod or shaft 11 by gravity. The upper side 18 is inclined away from the adjacent transverse plate or beam 19 so as to 85 allow the forward swinging of the upper end of the rib on the rod 12 as a pivot.

The center portion of the rib is formed in cross section as seen in Fig. 5. There is a 90 lateral flange 20 at each side of the rib below which the inner face is curved inwardly, as seen in Fig. 5, at 21, and it will be seen that when the ribs are closely spaced, as seen in Fig. 2, these ribs will provide a narrow slot 95 100.

between the flanges 20 to allow the passage of lint but as soon as the slot is passed there will be a side relief between the sets of the ribs, allowing the lint to expand as it is torn from the seed.

5 The lower end of the gin rib is also provided with a marginal flange 22 and an inner web 23, the web being slotted, as in the upper head of the rib, to engage over the rod or shaft 12. As will be seen from Fig. 1 the slot, in which the shaft 12 is received, is nearly vertical, but is inclined slightly forward from the shaft so that when the rib is in operating position, as shown in Fig. 1, there will be a 10 tendency of the rib to tip at its upper end against the shaft 11 and be held in place largely by gravity.

When the ribs are mounted in position on the shafts 11 and 12, as seen in Fig. 2, the 20 said rods will extend beyond the sides 24 of the gin housing, and be held in position by clamping nuts 25. When thus assembled on the shaft it will be seen that the flange 13 at the upper end of each rib, and the flange 22 25 at the lower end of each rib, will contact frictionally with the sides of the flanges on the adjacent ribs. The said flanges are elongated, as shown in the drawing, so as to provide a frictional surface of some extent between adjacent ribs so that when they are clamped together on the rods there will be no play or opportunity for lateral movement of the gin ribs relative to each other. They will be held rigidly in position so that there 30 is no liability for the ribs becoming out of alignment or to fail to keep the proper position relative to the gin saws. The ribs are assisted in being held in position also by the manner of engagement between the ribs and 35 the two supporting rods 11 and 12. This will be obvious from Fig. 1.

The advantages of my construction lie not only in the more effective shape of the gin rib in cross section but also in the substantial 40 bearing between adjacent ribs, which keeps them in alignment. Furthermore, the ribs may be easily removed when desired. This is best done by releasing the clamping nuts 45 on the upper and lower rods and then 50 swinging the upper end of the rib forwardly on the lower rod as a pivot until the upper head of the rib is free of the transverse plate or beam 19, after which the rib may be drawn directly upward out of its position and a 55 new one inserted in its place. The further advantages of the device will be obvious to those skilled in the art.

What I claim as new is:

1. In a cotton gin, a housing, a gin saw 60 mounted therein, gin ribs mounted adjacent said saw, upper and lower heads on said ribs, marginal flanges on said heads adapted to contact with the heads on adjacent ribs, said heads having slots the open sides of which 65 are inclined downwardly to fit about sup-

porting rods, and means to clamp said ribs together.

2. In a cotton gin, a housing, gin saws therein, transverse rods above and below said saws, gin ribs having downwardly inclined 70 slots the open sides of which are directed at a downward inclination to engage over said rods, and marginal flanges at the ends of said ribs adapted to contact with adjacent ribs to hold said ribs aligned and means to clamp 75 said ribs together.

3. A cotton gin including a housing, transverse rods mounted therein, gin ribs having upper and lower heads, said upper head being formed with a slot directed downwardly and rearwardly to engage one of said rods, the lower head having an elongated slot extended downwardly to receive one of said transverse rods, and means to clamp said ribs on said rods.

4. A cotton gin including a housing, a gin saw therein, transverse rods in said housing, gin ribs having their ends slotted to engage said rods the lower slotted end opening downwardly whereby said ribs are retained thereon by gravity, elongated later flanges at the ends of said ribs adapted to contact with adjacent ribs to maintain alignment of said ribs and means to clamp said ribs in 90 position.

In testimony whereof I hereunto affix my signature this 7th day of April, A. D. 1930.

JOHN ARNOLD STREUN.

CERTIFICATE OF CORRECTION.

Patent No. 1,849,773.

Granted March 15, 1932, to

JOHN ARNOLD STREUN.

It is hereby certified that error appears in the printed specification of the above numbered patent requiring correction as follows: Page 2, line 91, claim 4, for "later" read lateral; and that the said Letters Patent should be read with this correction therein that the same may conform to the record of the case in the Patent Office.

Signed and sealed this 17th day of May, A. D. 1932.

(Seal)
